E. P. LARSH
BY
D. R. WALKER
ATTORNEY

UNITED STATES PATENT OFFICE.

EVERETT P. LARSH, OF DAYTON, OHIO.

SHORT CIRCUITER.

Application filed January 10, 1922. Serial No. 528,223.

To all whom it may concern:

Be it known that I, EVERETT P. LARSH, a citizen of the United States, residing at Dayton, in the county of Montgomery and State of Ohio, have invented certain new and useful Improvements in Short Circuiters, of which the following is a specification.

This invention relates to electric motors and more particularly to a short circuiting or operation changing device for alternating current motors of the repulsion induction type, by which the motor is automatically changed from a repulsion starting condition 10 to an induction running condition and vice-versa in accordance with variations of speed.

The object of the invention is to simplify the structure as well as the means and mode of operation of such circuit changing devices whereby they will not only be cheapened in construction, but will be more efficient in use, automatic in operation, uniform in action, automatically controlled, and unlikely to get out of repair.

A further object of the invention is to provide improved means operated by centrifugal tendency by which the commutator bars are automatically connected with a common electrical conductor, which will 20 promptly respond to variations of speed above and below a predetermined rate of rotation.

A further object of the invention is to provide a short circuiting or current changing device, which will have a wiping action insuring perfect electrical contact, in which this wiping action will be further effected under yielding pressure thereby obviating any chatter or vibration and the incident 30 arcing and burning of the contact surfaces.

A further object of the invention is to provide means for controlling the movement of the short circuiting or current changing members whereby their movement 40 to effect the alternation of the motor from repulsion to induction operation and vice-versa will be effected by a quick movement in either direction.

A further object of the invention is to provide such a short circuiting or current changing device which will be compact, of few parts, and having no pivot joints, nor indirect movement, but in which the current controlling devices are directly operated by centrifugal tendency.

With the above primary and other inci-

dental objects in view as will more fully appear in the specification, the invention consists of the features of construction, the parts and combinations thereof, and the mode of operation or their equivalents, as hereinafter described and set forth in the claims.

Referring to the accompanying drawings, Fig. 1 is a sectional view of a motor commutator and the short circuiting device forming the subject matter hereof applied thereto. Fig. 2 is an end elevation partly broken away of the short circuiting device and commutator. Fig. 3 is a detail sectional view of the contact members shown in Figs. 1 and 2, in operated or contacting position. Fig. 4 is a perspective view of the short circuiter off the shaft. Fig. 5 is a detail sectional view of a modification of the construction shown in the preceding figures, wherein the contact member moves diagonally to effect the wiping or sliding contact. Fig. 6 is a similar detail view of substantially the same construction as shown in Fig. 5, but employing double guide elements. Fig. 7 is a detail sectional view of a further modification, wherein the contact member is yieldingly mounted for oscillatory movement into and out of engagement of the commutator bars. Fig. 8 is a similar detail sectional view of a further modification, employing an intermediate contact, actuated by the movement of the centrifugally operated slugs or weights. Fig. 9 is a modification somewhat similar to Fig. 7, and Fig. 10 is a detail view of the driving vanes.

Like parts are indicated by similar characters of reference throughout the several views.

The structure of the electric motor per se, forms no part of the present invention, which pertains wholly to the short circuiting means for the commutator bars, by which the motor is caused to operate alternately as a repulsion motor and an induction motor.

An alternating current, repulsion-induction motor of the single phase type to which the present invention is particularly adapted is one which as the name indicates, starts as a repulsion motor and as the speed approaches its normal or maximum rate of rotation automatically changes its character, and runs as an induction motor. Briefly described it consists of a field or stator of laminated toothed construction having a

single winding thereon connected to the supply circuit and a progressively wound armature or rotor with a commutator engaged by brushes during the starting or 5 "repulsion" period together with speed controlled devices for short circuiting the armature windings thru the commutator after the armature has attained a predetermined speed, which speed controlled means in some 10 instances lifts the brushes from the commutator simultaneously with the short circuiting operation. There is no electrical connection between the stator and the rotor. The currents in the stator create an alternating flux which reacts on the rotor and induces its rotation. This type of motor, therefore, starts as a simple repulsion motor without compensating or auxiliary windings and operates as a repulsion motor until the 15 20 rotor or armature approaches a synchronous speed whereupon the speed controlled devices operate to automatically short circuit the armature winding thru the commutator. Thus the motor is automatically transformed from a repulsion type into an induction motor having what is essentially a squirrel cage rotor. It is the improvement 25 of the speed operated governing or short circuiting device which forms the subject 30 35 matter of the present invention. One of the advantages of a machine of this type is that it is inherently a constant speed motor having a high starting torque with low current consumption or minimum current surge.

35 The typical repulsion motor without compensation gives the most efficient starting torque possible while the single phase induction rotor with the squirrel cage armature or its equivalent affords, the most efficient motor when running.

40 A repulsion-induction type of motor combines these most desirable qualities in a single machine. As it possesses such high starting torque characteristics it is well adapted for operating machinery which starts under full load, as pumps, air compressors, and grinding mills. Requiring no 45 starter they are adapted for automatic control, or distance operation. They start quickly and operate quietly and smoothly.

50 The above is offered merely to facilitate a thorough understanding of the purpose of the invention, and with no intent nor desire that it shall in any way be construed as limiting or restricting the application or scope of the invention.

55 Inasmuch as the construction of the motor per se forms no part of this invention, it has not been illustrated. It is to be understood, 60 however, that the short circuiting means forming the subject matter hereof is applicable to various styles of motors of the character heretofore indicated. Referring to the drawings, 1 is the armature shaft, on 65 which is carried the usual commutator com-

prising the core 2 about the periphery of which are located a continuous succession of commutator bars 3, insulated from the core 2 and from each other by intervening bodies of insulating material 4. The commutator bars 3 project somewhat beyond the terminal face of the core 2, and are beveled or inclined on their inner faces as at 5, thereby affording a beveled peripheral flange upon the lateral face of the commutator. 70

75 The short circuiting means is embodied in a unitary structure capable of being assembled independent of the motor and applied thereto or removed therefrom without the necessity of disassembling either the motor or the short circuiting means. However, this short circuiting device may if desired be assembled directly upon the 80 85 motor shaft.

90 The short circuiting device comprises a disc or support 6, adapted to be secured upon the armature shaft 1 adjacent to the face of the commutator, but in spaced relation therewith. In the present instance the disc 6 has been shown secured by the clamp collar 7, by which the disc is securely pressed and clamped against a shoulder formed upon the armature shaft. Any other suitable means of mounting the disc may be employed. The disc is thus fixed in its relative position, in relation with the commutator, but it may be of flexible or yielding material, whereby it may be flexed to and from the lateral face 95 of the commutator to vary the spaced relation; or the disc may be of rigid, inflexible construction, or material. Mounted about the periphery of the disc 6 is an annular series of radially disposed bifurcated slugs or centrifugally controlled contact elements 100

105 9. These contact elements or slugs are somewhat wedge shaped or tapered, and are assembled side by side to form a continuous succession or band about the disc. The periphery of the disc extends within the bifurcation or slot 8 of the slugs 9, whereby the succession of slugs or centrifugally controlled weights, ride astride of the peripheral edge of the disc 6. This slot or bifurcation 8 of the slug is somewhat wider than the thickness of the disc 6, thereby allowing the slugs or contact elements a limited range of lateral or shifting movement upon the disc. In addition to their inner bifurcations or slots, the slugs or contact elements are notched on their outer edges or faces as at 10. Extending about the assembled series of contact slugs or elements 110 115 120 125 130 9 and engaging in the external notches or bifurcations 10 thereof, is an endless elastic band 12. This band 12 may be of any suitable or desired material or character, but for convenience of manufacture and assembly a helical wire spring having its ends interconnected to form an endless band of suitable

diameter has been shown. In lieu of this type of elastic band, a coiled wire spring, the convolutions of which extend entirely around the assembly of plugs or contact elements may be employed, or several convolutions of a flat spiral spring may be utilized.

The elastic band 12 of whatever character it may be tends to contract the plugs or contact elements 9 into their innermost positions.

The disc 6 with its assembly of slugs or contact members arranged astride the peripheral edge thereof, and retained in assembled position by the encircling elastic band 12 forms the short circuit unit, which may be made up independent of the motor structure, and applied thereto or may be assembled directly upon the motor shaft as is found most convenient or desirable. It is located in juxtaposition to the lateral face of the commutator core 2, with the inclined or beveled ends 5 of the bars overhanging the slugs or contact element 9 at the inner side of the unit.

To protect the assembly of slugs or contact elements from injury and from the accumulation of dirt, dust, grease or other foreign material, which might interfere with their perfect contact with the commutator bars, there may be provided adjacent thereto, a concave disc 13, also carried upon the armature shaft 1 and the periphery of which overhangs the circular series of slugs or contact elements. This concave disc is fixedly mounted upon the armature shaft in its relation with the short circuiting units and the commutator. In addition to its function of housing and protecting the assembly of contact elements or slugs 9, this disc 13 may become a common contact or conductor with which the slugs or contact elements engage while engaged with the beveled ends of the commutator bars to afford a wedging action. In other words, this cover or housing may become an abutment, against which the slugs or contact members engage at one time while engaging beveled ends 5 of the commutator bars at the other side. The slugs are wedged or driven into this relation by the centrifugal tendency as the unit is rotated. However, this disc or housing 13 is not essential and the device will operate successfully if the housing or abutment disc 13 is wholly omitted.

Centrifugal tendency induced by the rotation of the shaft 1, and the series of contact slugs 9, carried thereby, tends to move such slugs outwardly, against the tension of the elastic contracting band 12. Whenever the centrifugal tendency is sufficient to overcome the tension of the band 12, the slugs 9 in their outward movement will engage the beveled faces 5 of the overhanging ends of the commutator bar 4, and upon increased centrifugal influence will tend to slide out-

wardly upon such inclined faces. If the concave disc or housing 13 is employed, this movement may continue until the slugs or contacts engage the inner face of the concave disc or shell 13. It is to be noted that the shell or disc 13 is also provided with a beveled face 15. This bevel of the shell or disc 13 is, however, located somewhat more remotely from the center of rotation than the bevel 5 of the commutator bars. Thus the slugs will first engage the bevel 5 of the commutator bars, and will then slide or travel along these inclined surfaces in a diagonal direction before engaging the beveled face 15 of the shell or disc 13, whereupon the slugs will wedge themselves into firm contact within the angle formed by the respective beveled faces 5 and 6.

However, as before mentioned the concave disc 13 is not essential. If omitted, the slugs will have a somewhat similar action engaging the inclined faces 5 of the commutator bars and sliding diagonally thereon until limited in their outward movement either by the resistance of the elastic band 12, or a limiting ring 14 may be inserted within the helical band 12 to limit the outward movement of the slugs. The tension of the slugs or contact members 5 upon the ends of the commutator bars may be somewhat increased by making the supporting disc 6 of flexible or yielding material, whereby the pressure of the slugs upon the inclined faces 5 will tend to press the disc laterally, causing it to assume a somewhat concave form as shown in Fig. 3, and thereby utilizing the elasticity or resiliency of the disc to increase the contact pressure of the slugs upon the commutator bar. If on the other hand the disc or support 6 is of comparatively rigid material, the slugs are permitted ample side play or freedom of movement by the relation dimensions of the slot or bifurcations 10 and the thickness of the disc to effect a yielding lateral movement. The tendency of the slugs of course is to move directly outward in a plane perpendicular to the axis of rotation.

The engagement of the slugs with the beveled ends 5 of the commutator bar tends to force the slugs laterally out of this plane of normal movement and hence the slugs exert a wiping action under pressure upon the faces of the commutator bar. This insures a perfect clean contact. The wiping action of the slugs or contact members upon the bars keeps such surfaces clean and bright and prevents the accumulation of dust, grease or foreign material, which might otherwise insulate such contacts.

In Fig. 5 there is shown a modification wherein the bifurcated slugs are mounted upon a concave disc 16, fixedly mounted upon the shaft 1, with its concave side toward the commutator and hence its periph-

ery is inclined in such direction. In this instance the commutator bars do not overhang nor possess the inclined ends 5, but terminate in a plane perpendicular to the axis of rotation. The contact slugs 9 are quite similar to those previously described, being bifurcated at 10 to ride astride the periphery of the concave disc and notched at 8 to receive the elastic retaining band 12. The elastic band 12 is made up of a helical spring, the ends of which are joined together, may enclose a limiting ring 14 as before described, which will limit the outward throw of the contact slugs. While the normal tendency of these slugs or contact elements will be to move radially in a plane perpendicular to the axis of rotation, the inclination of the supporting disc will guide the slugs or contact elements inwardly toward the commutator bars in a diagonal path of travel. The slugs at their limit of movement will engage the ends of the commutator bars with a wiping or sliding engagement, which will insure a perfect clean contact. The greater the speed, the greater will be the pressure of the contact members upon the commutator bars, and this engagement will in fact limit their outward throw, independent of any retaining ring 14 or any other limiting means. As in the first instance, the disc 16, may be flexible or yielding, whereby the elasticity or resiliency of such disc may be utilized as a spring pressure for the contact element. However such elasticity or yielding function of the disc is not essential and such concave disc 16 may be of substantially rigid construction. This construction differs from the primary construction in guiding the slugs or contact elements diagonally on to a flat surface, with which they make sliding contact, whereas in the primary construction the slugs were permitted to move in straight radial paths into contact with a diagonal surface.

In normal position when the rotor is at rest, or before it has attained its predetermined operating speed, the contact slugs 9 will be held in contracted position, upon the periphery of the disc by the band 12. However, as the rotor approaches the predetermined speed at which the operation changes from repulsion to induction mode of operation, the slugs will move outwardly against the tension of the elastic band 12 until they contact the commutator bars, whether such bars be of the overhanging tapered or inclined type shown in Fig. 1, or the flat faces to which the slugs move in a diagonal direction as shown in Fig. 5. Further increase in speed induces greater centrifugal influence, and the bevel face 5 of the commutator bars in the construction shown in Fig. 5 or the diagonal movement 65 of the slugs in Fig. 5 will have a camming

action by which the slugs in their outward movement are deflected, thus affording a wiping or rubbing contact between the slugs and the commutator bar. This wiping or rubbing action, induced by the diagonal or camming movement of either construction, insures a bright clean contact surface and perfect electrical engagement.

While the assembly of contact slugs 9 upon the supporting disc of either type will normally rotate in unison therewith independent of any driving engagement and moreover, any independent rotation or slippage in the assembly of slugs in relation with the supporting disc and commutator would be immaterial, there has been shown in Fig. 2 driving vanes, 17 projecting laterally from the supporting disc, intermediate succeeding slugs 9. There may be any number of these vanes provided as desired. In practice, three or four of such vanes have been found sufficient. The vanes 17 as illustrated comprise merely tongues or flaps of metal stamped from the disc 6 or 16 at spaced intervals and protruding between the successive slugs of the series, dividing the contact slugs into a plurality of groups and affording a positive driving connection between the assembly of slugs and the carrier therefor.

In Fig. 6 there is shown a construction quite similar to that of Fig. 5, except that in lieu of slotting or bifurcating the slugs to ride astride the periphery of the supporting disc 16, the slugs are interposed between two parallel concentric spaced concave discs 18-18. They are retained in their innermost position by the elastic band 12 and operate diagonally to engage the ends of the commutator bars exactly as before described. The guide disc 18 is mounted in spaced fixed relation upon the armature shaft, and the assembly of slugs located therebetween.

In Fig. 7 there is shown a further modification, wherein the bifurcated slugs ride upon the periphery of a disc, which may be either yielding or rigid, but the elastic retaining band is offset out of the plane of the points of engagement of the slugs effect an oscillatory or leverage movement outwardly 110 against the tension of such band, and inwardly under its influence.

In this construction, the supporting disc 20 is of offset flanged construction, although a simple flat disc such as shown in Fig. 1 might be employed with a second disc to form a rest or stop for the slugs. The slugs are notched or bifurcated at 21 to engage over the periphery of the supporting disc, while they are also notched or recessed on the opposite edge at 22 to receive the elastic band 12. There is preferably provided a retaining disc or housing 23 of concave form, which overhangs the supporting or fulcrum ends of the slugs to retain 130

the series of slugs in their assembled relation. Under centrifugal influence the inner ends of the slugs tend to move outward, the slugs fulcruming upon the edge of the 5 supporting disc, while their inner end tilt toward the overhanging commutator bars against the tension of the elastic band 12. The commutator bars in this instance, are provided with the inclined faces 5 before 10 mentioned, and the slugs have a wiping or sliding engagement thereon. If the supporting disc is of flexible or yielding material, it may yield laterally under the pressure of the slugs upon the inclined face 5 15 to permit such slugs a greater range of sliding movement, and such elasticity or spring of the disc is utilized to insure perfect contact at all times. In this instance the supporting disc 20 and the retaining or housing disc 23, are preferably mounted upon or secured to a collar or hub 24, which in turn is mounted upon the armature shaft 1.

The construction shown in Fig. 8 differs from those previously described thru the 25 fact that the slugs or centrifugally controlled members do not directly engage the commutator bars, but in lieu thereof, the 30 centrifugally controlled slugs 9 are enclosed or housed within a peripherally flanged or cup disc 26, the marginal flange of which is slotted to form a succession of tongues or yielding fingers 27, overhanging the peripheral faces of the assembly of slugs. The 35 slugs in their outward movement against the resistance of the elastic band 12 engage the flexible overhanging fingers or tongues 26, flexing such fingers outwardly into wiping engagement with the metal faces of the commutator bar. To insure a clean wiping contact, the extremities of the flexible fingers 40 or contact slugs 26 are preferably bent outwardly and backwardly to afford bearing surfaces or contact shoes of greater extent. The slugs are retained within the overhanging 45 fingers or contact tongues, intermediate the supporting disc, and the core of the commutator. If a unitary structure is desired, capable of being removed from and applied to motors, as a unit, the disc may be mounted 50 upon a collar or hub 28 which carries at the inner side of the series of slugs a second disc or ring 29 to retain the slugs or centrifugally controlled members when the unit is removed from the motor.

55 From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

60 While in order to comply with the statutes

the invention has been described in language more or less specific as to structural features, it is to be understood that the invention is not limited to the specific details shown, but that the means and construction 70 herein disclosed comprises the preferred form of several modes of putting the invention into effect, and the invention is therefore claimed in any of its forms or modifications within the legitimate and 75 valid scope of the appended claims.

Having thus described my invention I claim:

1. In a short circuiting device for commutators, a circular series of independent 80 contact slugs concentrically arranged in juxtaposition to the lateral face of the commutator and movable radially into engagement with the commutator bars by centrifugal influence, said slugs being bifurcated 85 on their inner ends, a supporting and guide disc the periphery of which is straddled by the bifurcated slugs and a contractile band against the tension of which the series of slugs is capable of distention under centrifugal influence.

2. In a short circuiting device for commutators, a disc mounted in a parallel plane spaced from the lateral face of the commutator, bifurcated contact slugs 95 arranged in a concentric series about said disc with their furcations straddling the periphery of the disc, and an elastic band against the tension of which the slugs are movable into engagement with the commutator bars by centrifugal influence.

3. In a short circuiting device for commutators, a circular series of independent contact slugs concentrically arranged in juxtaposition to the lateral face of the commutator, an elastic band against the tension of which the slugs are radially movable under centrifugal influence, and means for guiding said slugs in a direction inclined to the axis of rotation into contact with the 100 commutator bars during their movement under centrifugal influence.

4. In a short circuiting device for commutators, an expandable and contractible series of contact elements controlled by centrifugal influence and means for guiding said elements diagonally into contact with the commutator bars while being expanded under centrifugal influence.

5. In a short circuiting device for commutators, a concavo-convex disc located in spaced relation with the lateral face of the commutator, an expandable and contractible series of contact members controlled by centrifugal influence, said contact members 115 being guided by said concavo-convex disc during the movement under centrifugal influence in a direction inclined to the axis of rotation.

6. In a short circuiting device for com- 120

- 6
- mutators, a concavo-convex disc located in spaced relation with the lateral face of the commutator, a circular series of bifurcated contact slugs mounted about the periphery of the disc with their furcations straddling the edge of the disc, said circular series of contacts being expansible under centrifugal influence and guided diagonally into contact with the commutator bars by said disc 10 during the expansive movement.
7. In a short circuiting device for commutators, a series of contact slugs having notches in their opposite edges, a disc positioned in spaced relation with the lateral face of the commutator over the periphery of which the notches in the inner edges of the slugs engage, and an elastic band engaging in the notches in the outer edges of the slugs against the tension of which the 15 series of slugs is movable into engagement with the commutator bars against centrifugal influence.
8. In a short circuiting device for commutators, a circular series of H-shaped con-
- tact slugs, a supporting disc therefor 25 engaging between the furcations of one end of the slugs, and an elastic band engaging between the furcations of the opposite end of the slugs against the tension of which the series of slugs is expansible into contact 30 with the commutator bars under centrifugal influence.
9. In a short circuiting device for commutators, a circular series of centrifugally actuated contact slugs having notches in 35 their inner edges, expansible into contact with the commutator bars under centrifugal influence, and a supporting disc about the periphery of which the slugs are arranged with the periphery of the disc normally engaging within said notches.

In testimony whereof, I have hereunto set my hand this 22nd day of November, A. D. 1921.

EVERETT P. LARSH.
